TRAIL GRADER

Harold E. Miller, P.O. Box 98, Milwaukee, Wis. 53201
Filed Nov. 18, 1964, Ser. No. 412,009
17 Claims. (Cl. 37—108)

ABSTRACT OF THE DISCLOSURE

A trail grader having a pair of carriage frames wheel mounted for rolling on spaced rails at the opposite sides of a roadbed and a center beam assembly interconnecting the carriage frames and including a pair of tubular beams of different sizes arranged to slide one within the other in telescopic relation to accommodate variations in the distance between the carriage frames as the width of the roadbed and the distance between the rails varies. The center beam assembly is vertically adjustable and compacted stiffening particulate is confined within the smaller tubular beam to provide rigidity.

This invention relates generally to road building apparatus and more particularly to apparatus for preparing roadbed and similar surfaces prior to the laying of concrete, asphalt or similar pavement thereon.

Generally in the construction of roadway such as concrete or asphalt highway, where conditions are such as to require it, a rough grade of the ground surfaces is obtained by power tools such as tractors or the like. Form rails are then placed on both sides of the roadbed and carefully leveled and spaced in accordance with the requirements of the desired finished pavement.

In order to provide a final grade for the ground surfaces an apparatus generally referred to as a trail grader is employed. The trail grader is placed on the form rails and rolled therealong by wheels provided for that purpose. A cutting blade or plate is suspended between the wheels in a direction transverse to the rails and is pulled by means of a cable assembly or the like along the rails to traverse the roadbed. The cutting plate is generally segmentally constructed to provide for desired crown, and the height of the plate with respect to the wheels and rails is carefully adjusted, the top of the rails usually being established as a point of reference.

In modern highway construction the width of the roadway often converges or diverges, as for example, in the case of aprons or approaches leading to the main lanes of a super highway. In the construction of such approaches the narrowing of the distance between the form rails should conform to the desired width of the pavement, and as a consequence in traversing such approaches for leveling purposes the width of the trail grader should vary in accordance with the narrowing attitude of the form rails.

In addition, depending on the cutting depth, soil conditions, equipment capacity and other factors, it is often necessary to traverse the trail grader over the ground surfaces more than once, varying the depth of the cutting plate with each successive cut until the final finished grade is achieved.

Such considerations make manifest the desirability of providing means for easily and continuously changing the width of a trail grader and also for changing the cutting depth of the blade with respect to the form rails.

2

Accordingly, it is an object of the present invention to provide a trail grader wherein the width or transverse length of the cutting plate can be continuously varied to conform to changes in the width of the roadbed or the distance between the form rails.

Another object of the invention is to provide a trail grader having means for easily and continuously changing the height of the cutting plate with respect to the form rails in order to accommodate variations in the desired final level of the grade as well as to provide for variations in cutting depth with successive passes over the ground surfaces.

Another object of the invention is to provide means for increasing the rigidity of the supporting members of the cutting blade or plate.

Another object of the invention is to provide a trail grader having provision for continuous adjustment of both cutting width and depth, but wherein the adjustment apparatus is power operated and controllable by a single operator.

Still another object of the invention is to provide a trail grader of the type described which includes a provision for increasing the width or the transverse length of the cutting blade beyond the normally available width of the cutting blade.

Yet another object of the invention resides in the provision of a manual adjustment mechanism for making rough changes in the setting of the cutting blade height and a pneumatically operated adjustment mechanism for making fine changes in cutting blade height.

Another object of the invention is to provide a trail grader of the type described which is designed and constructed for heavy-duty applications, is simple to operate, provides for continuous adjustment of cutting width and height, is relatively inexpensive in manufacture and which is capable of serving a long, useful operating life.

Many other features, advantages and additional objects of the present invention will become manifest to those versed in the art upon making reference to the detailed description which follows and the accompanying sheets of drawings, in which preferred structural embodiments incorporating the principles of the present invention are shown by way of illustrative example only.

In the drawings:

FIGURE 1 is a perspective view of a trail grader which incorporates the principles of the present invention, with portions thereof cut away for clarity;

FIGURE 2 is a fragmentary plan view of the invention illustrating the connection between a pair of center beam assemblies and a vertical adjustment beam;

FIGURE 3 is similar to FIGURE 2 but includes a beam spacer member interposed between the center beam assemblies and the vertical adjustment beam for extension of the center beam assemblies;

FIGURE 4 is a vertical cross-sectional view of the center beam assemblies of the invention and including a beam stiffener member shown partly in elevation;

FIGURE 5 is a fragmentary plan view of the center beam assemblies connected at the ends thereof to a pair of vertical adjustment beams;

FIGURE 6 is an elevational side view of the invention with parts removed for clarity and with a vertical adjustment beam thereof illustrated in a raised and in a lowered position; and

FIGURE 7 is a perspective view of the center beam stiffener member illustrated in FIGURE 4.

As shown in the drawings:

Although the principles of the present invention are of utility in any road building apparatus, a particularly useful application is made to trail graders and the illustrative embodiment herein shown at reference character 10 in FIGURE 1 consists generally of a pair of spaced end members or carriage frames 11 and 12 interconnected by a center section indicated generally at 13.

Each of the carriage frames 11 and 12 comprises an elongated carriage beam 14, rectangularly shaped in cross-section and having mounted at the ends thereof a pair of wheels 16, 16 for engaging and for being rolled along one of a pair of spaced form rails 17, 17.

In order to mount and to control the height of the center section 13, an elongated vertical adjustment beam 18 is carried on each of the carriage beams 14. Each of the beams 18 comprises a pair of vertical side plates 19 and 20 and a pair of horizontally extending top and bottom plates 21 and 22. As noted, the vertical adjustment beams are hollow and the horizontal space between the inner surfaces of the side plates 19 and 20 is substantially equal to the horizontal distance between the outside faces of a pair of side plates 23 and 24 of their respective carriage beams 14. The vertical distance, however, between the inside face of the top and bottom plates 21 and 22 is considerably greater than the vertical distance between the outside faces of corresponding top and bottom plates 26 and 27 of their respective carriage beams such that the vertical adjustment beams are capable of vertical movement on the carriage beams but are essentially stationary in a lateral direction with respect to the beams.

As noted, situations arise in certain types of pavement construction when the roadbed, and accordingly the form rails 17, 17, do not extend in parallel relation, but may converge as, for example, in the construction of an approach to the main lanes of a super highway. Accordingly, the center section 13 of the present invention, which constitutes the actual cutting or grade leveling portion of the invention, is telescopically extensible to accommodate constantly varying widths between the form rails 17, 17 and correspondingly the carriage frames 11 and 12.

Accordingly, the center section 13 comprises a pair of center beam assemblies 28 and 29, each of which comprises a pair of tubular or elongated hollow complementarily shaped beams, one of which is larger in cross-section as indicated at 30 and the other of which is smaller in cross-section as indicated at 31, with the inside dimensions of the larger beam and the outside dimensions of the smaller beam being sized such that the smaller beam slides snugly yet freely within the larger beam in telescopic relation. It will be appreciated that although the illustrative beams which comprise the center beam assemblies are rectangular in cross-section for increased strength, beams having other cross-sectional configurations could also be advantageously utilized.

The beam assemblies 28 and 29 extend in spaced parallel relation between the carriage frames 11 and 12 and it will be noted that the assemblies are in vertical alignment, that is, beam assembly 29 is situated directly ahead of assembly 28 in the direction in which the apparatus 10 moves along the form rails 17, 17 during a leveling operation.

Connected in fixed assembly to a front face 32 of each of the larger beams 30 is a downwardly depending slightly forwardly inclined plate or cutter holder 33 which extends transversely along the length of the larger beam 30 and which is formed with a plurality of horizontally extending slots 34 at spaced points along the length thereof. A plurality of eye bolts 35 are threaded, welded or otherwise securely fastened to each face of the cutter holders 33 in spaced relation to receive the ends of cables

or the like tension members connected to a tractor or other power apparatus for pulling the grader along the rails 17, 17.

Attached to each of the cutter holders 33 by means of nut and bolt assemblies 36 or other fastening means are a plurality of individual cutting or leveling plates 37, which extend along the length of the cutter holders and which actually engage and level the grade of the ground or like surface. The cutting plates 37 are adjustable in the slots 34 in order to accommodate a crown or other transversely irregular contour of the ground surface. A plurality of bracer plates 38 are welded to the cutter holder plates 33 and the larger beams 30 at spaced intervals along the length thereof in order to provide additional strength to the cutter holders 33.

In order to increase the strength and to minimize "bowing" in a transverse direction of the center section 13 as the individual center beam assemblies 28 and 29 are in an extended condition, the larger and smaller beams 30 and 31 of assemblies 28 and 29 are reversed with respect to their relationship and connection to the carriage frames 11 and 12. For example, referring to FIGURE 5 the larger beam 30 of the center beam assembly 28 is connected to the carriage frame 11 and the smaller beam 31 thereof is connected to the carriage frame 12. Such arrangement is reversed, however, with respect to the center beam assembly 29 such that when the center section 13 is extended a larger beam 30 of at least one of the assemblies 28 and 29 is intersected by a transversely extending plane at all points along the entire length of the center section 13.

It will be apparent that the larger beams 30 have an increased rigidity factor with respect to the smaller beams 31 which are telescopically received therein and in order to increase the rigidity of the smaller beams 31 to more closely approximate that of the larger beams 30 the smaller beams may be filled completely or at certain portions thereof with compacted particulate matter such as sand, fine gravel or the like as indicated at reference numeral 39 in FIGURE 4. Such particulate matter also increases the mass of the center section 13, such additional mass being particularly advantageous when preparing relatively unyielding or hard surfaces, such as hard clay, to oppose a tendency of the grader to raise or "climb" as the cutting plates engage such hard surfaces.

In order to further reduce transverse "bowing" of the center section 13, particularly when the section is extended and the ground or soil conditions or the like are extremely hard, means are provided to interconnect the center beam assemblies 28 and 29 in "locked-together" relation.

Referring to FIGURES 4 and 7, a beam connector or stiffener bar 40 which, in the illustrated embodiment, comprises a short, hollow, rectangularly shaped beam, is provided with a pair of spaced tubular stubs 41 and 42 depending downwardly therefrom. A tubular sleeve 43 having an outer diameter substantially equal to the transverse or lateral distance between the larger beams 30 of the assemblies 28 and 29 is connected in fixed assembly to a back face 44 of the larger beam 30 of the assembly 29, as for example, by means of a weld 46.

When the stiffener bar 40 is mounted in place, the stud 42 thereof, which has an outer diameter substantially equal to the inner diameter of the sleeve 43, is inserted downwardly into the sleeve, the other stud 41 being slipped downwardly over a back face 46 of the assembly 28. The distance between studs 41 and 42 and the diameters thereof are such that when the stiffener bar 40 is mounted in position the beam assemblies 28 and 29 are "locked together" in a transverse direction. It will be appreciated that more than one stiffener bar can be mounted across the portions of the beam assemblies 28 and 29 having overlapping larger beams, and in addition the bars 40 can be arranged and dimensioned to be effectively utilized even along portions of the beam assemblies

28 and 29 wherein the larger beams 30 thereof do not overlap. Such arrangement would, of course, lock the larger beam of one center beam assembly with the smaller beam of the other center beam assembly.

Referring to FIGURES 1 and 2, the beam assemblies 28 and 29 are secured to the carriage frames 11 and 12 in the illustrative embodiment in the following manner. Corresponding ends of a larger beam 30 and a smaller beam 31 adjacent one of the carriage frames is secured in fixed assembly by means of a weld connection or the like to a flat vertical beam supporting plate 48 removably mounted on a complementary flat vertical carriage plate 49 by means of a plurality of fasteners such as the threaded bolts at 50. The carriage plate 49 is connected in fixed assembly to the side plate 20 of the vertical adjustment beam 18.

In order to extend the length or the transverse width of the center section 13 beyond the permissible telescopically extensible length thereof, a beam spacer member indicated generally at reference character 51 in FIGURE 3 may be inserted between the beam supporting plate 48 and the carriage plate 49. The spacer member 51 is more particularly characterized as comprising a pair of spacer beams 52 and 53 aligned generally coaxially with the beams of the respective center beam assemblies 28 and 29 and dimensioned in a longitudinal direction in accordance with the desired additional length requirements of the center section 13. A pair of spacer plates 54 and 56 are welded at the ends of the spacer beams 52 and 53 and are joined, respectively, to the beam supporting plate 48 and the carriage plate 49 by fastener members 57.

In order to provide "full width" cutting effect of the center section 13 with the spacer member 51 incorporated therein, a cutter holder 33 and cutting plate 37 are attached to the front spacer beam 53.

As noted, one of the features of the invention resides in the provision of means for continuously varying the width of the center section 13 to conform to changes in width of the form rails 17 and to that end a dual-acting hydraulic cylinder 58 is mounted on the top face of the larger beam 30 of the "forward" center beam assembly 29. A telescopically extensible piston member 59 is connected at a distal end 60 thereof to the beam supporting plate 48 of the carriage frame 11.

A pair of conduits 61 and 62 communicate opposite ends of the cylinder 58 with a source of pressurized fluid which, in the illustrated embodiment, comprises a motor-pump assembly 63 mounted on a platform 64 which may be connected in fixed assembly both to the larger beam 30 of the forward beam assembly 29 and to the side plate 20 of the vertical adjustment beam 18 mounted on the carriage frame 12.

A control box 66 includes a plurality of control levers 67 which may be mounted in the conduits 61 and 62 for actuating the cylinder 58. A cover member 68 may be mounted on the beam assembly 29 in order to house the hydraulic cylinder for purposes of protection.

As noted, the beam assemblies 28 and 29 are connected to the vertical adjustment beams 18 by means of the beam supporting and carriage plates 48 and 49. In order to provide vertical adjustability for the beam assemblies means are provided for pivoting the vertical adjustment beams 18, 18 upwardly and downwardly as well as for adjusting the fulcrum or pivotal point of the beams.

As best illustrated in FIGURE 6, a pin and port arrangement is situated near one end 68 of the vertical adjustment beam 18 and comprises a plurality of vertically spaced ports 69 which extend horizontally across the width of the beam 18. A single complementary shaped port 70 is formed in the carriage beam 14 and is alignable with any of the ports 69 for receiving a pin 71 to maintain the end 68 of the beam 18 in a desired position of adjustment and for providing a fulcrum for the beam 18.

An opposite end 72 of the beam 18 is interconnected to the carriage beam 14 by means of a hydraulic cylinder 73 pivotally connected at a lower end 74 thereof to the carriage beam 14 and at an upper end 76 thereof to a web flange 77 which is welded or otherwise permanently affixed to the beam 18. A pair of conduits 78 and 79 communicate pressurized fluid from the motor-pump assembly 63 to the cylinder 73 through actuating control levers as at 67 on the control box 66.

It will be appreciated that the pin and port adjustment arrangement as manifested by the ports 69 and the pin member 71 can be utilized for a rough adjustment in height of the vertical adjustment beams 18 (and correspondingly the height of the center beam assemblies 28 and 29) and the hydraulic cylinder 73 can be utilized for fine adjustment.

Not infrequently, after the cutting depth of the cutting blades 37 has been carefully adjusted with respect to the elevation of the form rails 17, the top surfaces of which are generally established as an elevational reference point, more than one pass over the ground surface must be performed in order to obtain a close tolerance grade. In such circumstances, after the trail grader has traversed a section of the roadbed it is moved back for another "cut" or over the section. It is advantageous, during such backward travel, to raise the cutting plates away from the ground surfaces.

Generally any change in vertical disposition of the cutting plates requires a complete readjustment when the cutting plates are again lowered to their proper cutting height. In order to avoid the necessity for such readjustment the present invention includes means enabling the cutting plate to be raised above the ground surface and then lowered again to its predetermined cutting height without readjustment thereof.

Thus, a vertical threaded stop stud 80 is mounted in a complementary threaded member of the vertical adjustment beam 18 as, for example, the top plate 21 thereof, and can be adjusted such that after the beam 18 has been pivoted to an upward position as indicated by the dashed lines in FIGURE 6 by means of the hydraulic cylinder 73, and is to be lowered again to a cutting position as indicated by the solid lines of FIGURE 6, a lower end portion 81 thereof will abut the top plate 26 of the carriage beam 14 to thereby prevent further downward movement of the beam 18. Consequently once the stop stud is adjusted to provide a working or cutting height of the cutting plate 37, the vertical adjustment beam 18 can be raised and lowered successively without again making reference to the elevation of the form rails 18 while maintaining a predetermined cutting elevation in its lower portion. Of course, a change in position of the pin members 71 with respect to the ports 69 at the opposite ends of the beams 18 would necessitate a readjustment of the beam 18 and the cutting plates 37 by again making reference to the elevation of the form rails 17.

As best seen in FIGURE 1, the wheels 16 may be provided with axially spaced flanges 82, 82 at the side faces thereof for guiding the wheels along the top surfaces 60 of the form rails, particularly in circumstances where the form rails do not extend in parallel relation but instead slightly converge or diverge as, for example, in super highway approach construction.

Although minor modifications might be suggested by those versed in the art, it should be understood that I wish to embody within the scope of the patent warranted hereon all such modifications as reasonably come within the scope of my contribution to the arts.

I claim as my invention:

1. A trail grader for preparing roadbed and the like surfaces comprising:
a pair of spaced carriage frames each provided with wheels for riding on spaced form rails,
a center beam section comprising a pair of elongated,

tubular center beams arranged one within the other in mutually telescopic relation with each being connected at one end thereof to one of said carriage frames, cutting plates affixed to said center section for engaging and preparing such roadbed, and dual-acting power means interconnecting said center beams to provide selective telescopic change in overall length thereof and to control the spacing of said carriage frames to conform to the spacing of the rails.

2. A trail grader for preparing roadbed and the like surfaces comprising:

a pair of carriage frames each provided with wheels for riding on one of a pair of spaced substantially parallel rails, a center beam section comprising a pair of elongated center beam assemblies extending transversely between the rails and interconnecting said carriage frames,

said center beam assemblies being vertically aligned and transversely spaced with each of said assemblies comprising:

a pair of tubular center beams arranged one within the other in mutually telescopic relation,

each of said center beams being connected at opposite ends thereof to said carriage frames,

cutting plates affixed to each of said center beam assemblies for engaging and for preparing such roadbed, and

dual-acting power means interconnecting said center beams of at least one of said assemblies to selectively telescopically actuate said one assembly for controlling the spacing of said carriage frames to conform to the spacing of the rails.

3. A trail grader for preparing roadbed and the like surfaces comprising:

a pair of carriage frames each provided with wheels for riding on spaced substantially parallel form rails, a center mean assembly comprising a pair of hollow center beams interconnecting said carriage frames and extending transversely to such rails,

one of said beams being undersized to be telescopically received in the other of said beams for varying the spacing between said carriage frames, and

compacted particulate matter in said undersized beam to increase the rigidity thereof with respect to the other beam.

4. A trail grader for preparing roadbed and the like surfaces comprising:

a pair of carriage frames each provided with wheels for riding on spacer substantially parallel form rails, a center beam assembly comprising a pair of elongated hollow rectangularly shaped telescopically arranged center beams extending transversely between said carriage frames and connected at opposite ends of the center section to the adjacent carriage frames, cutting plates affixed to the larger of said center beams for engaging and for preparing said roadbed, and a quantity of particulate matter compacted in the smaller of said center beams to increase the rigidity thereof.

5. A trail grader comprising:

a pair of carriage frames adapted to move along a pair of form rails,

a pair of center beam assemblies extending transversely between said carriage frames in spaced parallel relation,

each of said assemblies comprising a pair of elongated telescopically arranged center beams having overlapping inner ends and outer ends adjacent respectively said carriage frames,

means including an elongated beam spacer member to be interposed between the beam assemblies and one of said carriage frames to effectively increase the length of said center beam assemblies, and fastening means to detachably connect said center beam assemblies and said beam spacer member to said carriage frames for quick assembly and disassembly of the grader and for selectively increasing the effective width thereof with said beam spacer member.

6. The trail grader as defined in claim 5 and including cutting plates affixed to said center beam assemblies and to said beam spacer member for engaging and for preparing a roadbed surface along the entire length of said extended center beam assemblies.

7. A trail grader comprising:

a pair of carriage frames adapted for movement along spaced substantially parallel form rails, and a pair of center beam assemblies extending transversely between said carriage frames,

each of said assemblies comprising:

an elongated larger hollow beam connected to one of said carriage frames, and a complementary elongated smaller hollow beam connected to the other of said carriage frames and received in telescopic relation by its corresponding larger beam for widening the space between said carriage frames,

said beam assemblies being reversely arranged with respect to said carriage frames so that each of said carriage frames has a larger beam of one center beam assembly and a smaller beam of the other center beam assembly connected thereto to more nearly equalize the combined strength rigidity of the beam assemblies along the lengths thereof to minimize transverse "bowing" of the assemblies under load.

8. The trail grader as defined in claim 7 and including a quantity of particulate matter compacted within each of said smaller beams to increase the overall rigidity of said center beam assemblies.

9. A trail grader to be moved along a pair of substantially parallel form rails to prepare roadbed and the like surfaces comprising:

a pair of carriage frames each including:

an elongated carriage beam extending parallel to its corresponding rail, wheels mounted on said carriage beam for moving said carriage frame along its rail, and

an elongated vertical adjustment beam extending in juxtaposition to said carriage beam,

an elongated telescopically arranged center beam assembly extending transversely between said carriage frames and connected at the ends thereof to said vertical adjustment beams, and

mounting means for vertically movably mounting said vertical adjustment beams on their respective carriage beams and including means for selectively adjusting the vertical disposition of said vertical adjustment beams with respect to said carriage beams while said grader is in movement along the rails to correspondingly adjust the height of the center beam assemblies with respect to the rails.

10. A trail grader to be moved along a pair of form rails to prepare roadbed and the like surfaces comprising: a pair of carriage frames each including:

an elongated carriage beam extending parallel to its respective rail,

wheels mounted on said carriage beam for moving said carriage frame along its form rail,

an elongated vertical adjustment beam extending along said carriage beam,

a center beam assembly extending transversely between said carriage frames and connected at the ends

thereof to said vertical adjustment beams intermediate the ends thereof, means at one end of each of said vertical adjustment beams to pivotally connect said one end to its respective carriage beam, and means at the opposite end of each of said vertical adjustment beams to provide selective vertical adjustment of said opposite end with respect to its corresponding carriage beam to pivot said vertical adjustment beams to vary the height of said center beam assembly with respect to the form rails. 10

11. In a trail grader,

a pair of carriage frames each comprising:

an elongated carriage beam having wheels mounted thereon for riding along one of a pair of spaced form rails, 15
a pair of elongated vertical adjustment beams extending, respectively, in juxtaposition to said carriage beams, means providing cooperating pin and port means on 20 said carriage beam and on said vertical adjustment beam at one end thereof to provide vertical adjustment and vertical pivotal movement of said vertical adjustment beam,

hydraulic cylinder means at the opposite end of said 25 vertical adjustment beam to vary the height of the opposite end thereof with respect to said carriage beam,

a center beam assembly extending between said carriage frames and connected at the ends thereof to said 30 vertical adjustment beams, and

cutting plates affixed to said center beam assembly for engaging and for grading roadbed and the like surfaces. 35

12. In a trail grader,

a pair of carriage frames each comprising:

an elongated horizontally extending carriage beam having wheels mounted thereon for rolling along a form rail, 40

an elongated vertical adjustment beam extending in juxtaposition to said carriage beam, pin means for pivotally connecting said vertical adjustment beam at one end thereof to said carriage beam,

power means interconnecting said carriage beam and said vertical adjustment beam to provide vertical pivotal movement of said vertical adjustment beam about said pin means, and

cooperating threaded stud and flange means on said carriage beam and on said vertical adjustment beam to provide a stop to limit the downward pivotal movement of said vertical adjustment beam with respect to said carriage beam, 45

a center beam assembly extending between said carriage frames and connected at the ends thereof to said 50 vertical adjustment beams, and

cutting plates affixed to said center beam assembly for engaging and for grading roadbed and the like surfaces. 55

13. The trail grader as defined in claim 12 wherein said vertical adjustment beam is hollow and has a given inside vertical dimension greater than the outside vertical dimension of said carriage beam and has an inside horizontal dimension substantially equal to the outside horizontal dimension of said carriage beam and wherein said carriage beam extends longitudinally through said vertical adjustment beam to provide vertical movement of said vertical adjustment beam while restricting lateral movement thereof. 60

14. In a trail grader for preparing roadbed and the like 70 surfaces,

a pair of carriage frames each comprising:

an elongated horizontally extending carriage beam, wheels mounted on said carriage beam for rolling along one of a pair of spaced form rails, 75

an elongated vertical adjustment beam extending in juxtaposition to said carriage beam, pin means pivotally connecting said vertical adjustment beam at one end thereof to said carriage beam, and

a first hydraulic power cylinder pivotally connected at the respective ends thereof to said carriage beam and to said vertical adjustment beam to provide pivotal movement of said vertical adjustment beam with respect to said carriage beam about said pin means,

a telescopically extensible center beam assembly extending transversely between said carriage frames and connected at opposite ends thereof to said vertical adjustment beam,

a second hydraulic power cylinder mounted on said center beam assembly to vary the length thereof, and

fluid pressure means for connecting a source of pressurized fluid to said hydraulic power cylinders including control means for continuously controlling the vertical adjustment and the length of said center beam assembly while said trail grader is moved along the form rails to accommodate changes in desired width and depth of such roadbed.

15. The trail grader as defined in claim 14 and including axially spaced flanges on said wheels to maintain said wheels on said form rails upon changes in the length of said center beam assembly.

16. A trail grader for preparing roadbed and the like surfaces comprising:

a pair of spaced carriage frames each provided with wheels for riding on spaced form rails,

a pair of telescopically extensible spaced parallel vertical aligned transversely extending center beam assemblies interconnecting said carriage frames,

cutting plates on said center beam assemblies for engaging and for grading such roadbed, and

means for stiffening said widening beams against "bowing" under a transverse cutting load comprising:

a horizontal stiffener bar extending transversely between said center beam assemblies, and means on said stiffener bar for engaging and maintaining said center beam assemblies in locked-together relation.

17. A trail grader for preparing roadbed and the like surfaces comprising:

a pair of spaced carriage frames each provided with wheels for riding on spaced form rails,

a pair of horizontally transversely extending vertically aligned center beam assemblies interconnecting said carriage frames,

said beams being horizontally spaced from one another a given distance in the direction transverse to said beams,

cutting plates on said beams for engaging and for grading such roadbed, and

means for stiffening said beam assemblies against bowing under a transverse cutting load comprising:

a horizontally disposed stiffener bar extending transversely to said beam assemblies,

a pair of tubular studs depending downwardly from said stiffener bar,

one of said studs being situated between the interfaces of said beam assemblies and having a given outside diameter,

a tubular sleeve connected in fixed assembly to the interface of one of said beam assemblies and having an outside diameter substantially equal to said given space and an inside diameter sized to receive said one of said studs in snug telescopic relation, and

the other of said studs being transversely spaced from said one stud to snugly abut the outside

11

face of the other of said beam assemblies to connect said beam assemblies in locked-together relation.
